Primary Examiner — Leanne Was-Englehart(74) *Attorney, Agent, or Firm* — CPST Intellectual Property Inc.; Brett J. Slaney(57) **CLAIM**

The ornamental design for a paving set, substantially as shown and described.

DESCRIPTION

FIG. 1 is an enlarged plan view of a first embodiment of the paving set taken from the environmental view of FIG. 2.

FIG. 2 is an environmental plan view of the paving set of FIG. 1 repeating as a tessellation.

FIG. 3 is an enlarged plan view of the paving set of FIG. 1 in an alternate state of use.

FIG. 4 is an enlarged plan view of a second embodiment of the paving set taken from the environmental view of FIG. 5.

FIG. 5 is an environmental plan view of the paving set of FIG. 4 repeating as a tessellation; and,

FIG. 6 is an enlarged plan view of the paving set of FIG. 4 in an alternate state of use.

The portions of the figures shown in broken lines illustrate features that do not form part of the claimed design.

1 Claim, 4 Drawing Sheets(56)
